DISCONNECTING SWITCH

Carl G. Koppitz, Greensburg, Pa., assignor, by
mesne assignments, to Railway & Industrial
Engineering Company, Greensburg, Pa., a cor-
poration of Delaware

Application August 5, 1937, Serial No. 157,606

15 Claims. (Cl. 200—48)

This invention relates to disconnecting switches for high voltage circuits, and particularly to disconnecting switches of the type in which a contact blade enters freely into a jaw element and 5 is then brought into firm contact engagement with the jaw element.

An object of this invention is to provide disconnecting switches including a pivotally mounted contact blade, and mechanism for expanding 10 or spreading the contact portions of the blade into firm engagement with the jaw element after the blade has completed its angular movement into the jaw element. An object is to provide a switch including a jaw element, a tubular contact blade having contact portions for engagement with the jaw element, and operating mechanism for imparting angular movement to the blade and for spreading the contact portions of the blade at the final stage of a closing movement of the switch. More particularly, an object 15 is to provide a pivoted contact blade of tubular form, and operating means for moving the blade into a jaw element and then deforming the blade to force portions thereof into firm engagement 20 with the jaw element.

These and other objects and advantages of the invention will be apparent from the following specification when taken with the accompanying drawings in which:

Fig. 1 is a side elevation, with the switch illustrated in closed position, of an embodiment of the invention;

Fig. 2 is a fragmentary plan view of the same;

Fig. 3 is a fragmentary longitudinal sectional view of the contact blade;

Fig. 4 is a transverse section on line 4—4 of Fig. 3;

Fig. 5 is a similar transverse section on the same plane but illustrating the parts in the positions which they assume when the switch is open;

Fig. 6 is a fragmentary vertical section through the end of a contact blade having a modified form of contact surfaces;

Figs. 7 and 8 are transverse sections illustrating the contact blocks of Fig. 6 in withdrawn and in closed positions, respectively;

Fig. 9 is a side elevation, with parts in section, of another form of contact blade;

Fig. 10 is an enlarged vertical section of the contact end of the blade; and

Figs. 11, 12 and 13 are transverse sections on the planes of Fig. 10 indicated as 11, 11, 12, 12 and 13, 13, respectively.

In the drawings, the reference numeral 1 identifies a fixed insulator which carries the jaw

element 2 of the disconnect switch. A similar fixed insulator 3 supports one end of the relatively fixed housing 4 and the other end of the housing is supported upon a rotatable insulator 5 which carries a shaft that extends through the 5 housing 4 and carries the crank arm 6 of the switch operating mechanism. The switch insulator columns are mounted in fixed position upon a supporting structure 7, and the column 5 has an arm 8 for connection to the mechanism (not 10 shown) for the manual or power actuation of the switch. Appropriate forms of connectors 9 are secured to the jaw member 2 and housing 4, respectively, for connecting the switch into a line.

The contact blade 10 is a relatively thin walled 15 tube of resilient metal of good electrical conductivity, such as phosphor bronze, that is secured to the yoke 11 which is pivotally supported on the housing 4. A shaft 12 extends along the axis of the tube 10 and is rotatably mounted in bearings 13 which are carried by the yoke 11 and a sleeve 14 that is fixed within the outer end of tube 10 by screws 15. A crank arm 16 is secured to the end of shaft 12 adjacent the pivotally supported end of the blade, and the crank arm is 20 connected to the crank 6 of the rotatable insulator column by the forked link 17 and the universal joint 18.

The described type of linkage is well known in the art and has the following operating characteristics. The crank 6 may be turned clockwise, as seen in Fig. 2, through about 180° to open the switch. During the initial portion of this clockwise movement of the crank 6, the force exerted upon the end of link 17 is in a plane 30 approximately parallel to the pivotal axis of the blade 10 and results in a rocking of the crank arm 16 about the axis of shaft 12. When the crank 6 has moved clockwise about 30°, the crank pulls the link 17 toward the left, as viewed in 35 Fig. 1, and this pull results in an angular movement of the entire switch blade 10 about its pivotal support on the housing 4. The initial movement of crank 6 for a switch in closing operation exerts a thrust upon the link 17 which rotates the entire blade from an approximately 40 vertical position into the illustrated position. The final portion of the movement of the crank 6 produces a lateral twist on the end of link 17 which results in a rocking movement of the crank arm 45 16 and shaft 12.

In accordance with this invention, the rocking or angular movement of the shaft 12 is employed to expand or spread the contact portion of blade 10 into firm engagement with the jaw element 2. 50 55

As shown in Figs. 4 and 5, the contact surfaces of blade 10 are provided by small strips or contact blocks 19, of silver or a non-oxidizing alloy, that are soldered or welded to diametrically opposed portions of the blade 10. The overall diameter of the contact blocks 19 is somewhat less than the width of the gap of the jaw element 2, and the contact blade therefore enters freely into the jaw element. The outer end of the shaft 12 carries eccentrics 20, 20' on which the eccentric rings 21, 21' are journaled. Headed studs 22, 22' extend through the upper and lower portions of the tubular contact arm 10 and are secured, respectively, to the eccentric rings 21, 21'. Cylindrical plates 23 are arranged between the heads of the studs and the tube 10 to distribute the pressure over a substantial portion of the thin walled tube.

The tubular blade is imperforate and substantially closed at its hinge end by the bearing 13 and at its outer end by a cap 24. The operating mechanism is thereby protected against dirt, water and ice. A jumper connection 25 of high electrical conductivity is preferably provided between the housing 4 and the tube 10 of the contact blade. Either the opening or the closing movement of the blade may be facilitated by spring mechanism in the housing 4. As shown in Fig. 3, the spring 26 is so connected to an arm 27 on the yoke 11 as to exert a force tending to retain the contact blade in closed position.

The eccentrics 20, 20' are diametrically opposed and so arranged on shaft 12 that the total effective length of the studs 22, 22' is a minimum when the crank arm 16 has reached its final switch-closed position. The vertical dimension of the tubular blade is therefore contracted by the rocking movement of the shaft 12 and the horizontal dimension of the contact blade is thereby enlarged. This movement forces the contact blocks 19 apart and brings them into firm engagement with the jaw element 2. The initial movement of crank arm 16 and shaft 12 at the opening of the switch rocks the eccentrics 40 into the positions illustrated in Fig. 5, and the resilient blade 10 is thus permitted to assume its normal circular configuration to withdraw the contact blocks from engagement with the jaw element 2.

The contact blade 10' need not be resilient when, as shown in Figs. 6 to 8, a pair of contact blocks 28 are pivotally supported within the tube 10' and have contact portions 29 that extend to the exterior of the tube where they are provided with non-oxidizing contact surfaces 30. The blocks 28 are of arcuate form and are loosely guided for rectilinear movement by pins 31 that extend through openings in the opposite ends of the blocks. The ends of leaf springs 32 engage the upper and lower ends of the blocks 28 and the intermediate portions of the leaf springs are spaced from the blocks in positions to be engaged by the cam 33. The cam 33 is formed as a sleeve that is mounted on the outer end of the shaft 12' and has a clutch section 34 at one end for engagement with a similar clutch section 35 that is keyed to the shaft 12'. The cam sleeve is retained on shaft 12' in the desired position of angular adjustment by nuts 36 threaded upon the outer end of the shaft. The cam sleeve is mounted in a roller bearing 37 in the end cap 38 of the blade 10'. The operating mechanism is well protected within the tubular blade as the tube 10' is circumferentially complete except for the openings through which the

contact projections 29 extend. The contact blocks 28 are supported upon the annular insert 39 by flat spring members 40 that tend to force the contacts 28 inwardly towards each other. The members 40 are of a resilient metal of good electrical conductivity, such as phosphor bronze, since these members carry the current from the contact blocks to the blade 10'.

The described embodiments of the invention employ the angular movement of the shaft to force the contact blocks into engagement with the jaw element. The construction illustrated in Figs. 9 to 13 provides a longitudinal movement of the shaft for expanding the contact blade. The structures for supporting and actuating the contact blade of Fig. 9 are or may be substantially identical with those illustrated in Figs. 1 and 2. The contact blade includes the yoke member 41 which carries the tubular sleeve 42 that is closed at its outer end by a cap 43. A shaft 44 is rotatably supported at the axis of the sleeve 42 and carries the crank arm 45 that is connected to the operating mechanism. A cam 46 is secured to the shaft 44 and has an inclined track for receiving the pin 47 that is fixed to the yoke 41. The angular movement of the shaft 44 thus results in an axial displacement of the shaft. The wedge member 48 that is secured to the outer end of shaft 44 is formed as a body of revolution having a conical surface which flares outwardly from the small diameter inner end of the wedge member. A pair of levers 49 extend along opposite sides of the wedge member 48 and are pivotally supported within the sleeve 42 by studs 50 that pass through the wall of the tube 35 and into the inner end of the levers. Rollers 51 are mounted in slots in levers 49 for engagement with the wedge member 48, and these rollers are held against the wedge member by bolts 52 that are threaded into the outer ends of the levers 49 and have heads that bear against the sleeve 42. Contact blocks 53 having non-oxidizing contact surfaces 54 are secured to bosses 55 that are pressed in the sleeve 42 at or near the transverse plane of the axis of rollers 51. The parts 40 are illustrated in the positions which they occupy when the switch is open. The smaller diameter portion of wedge member 48 is in engagement with the rollers 51 and the conical surface is initially adjacent the rollers in position to be drawn between the same by a movement of shaft 44 to the left, Fig. 11. Pressure thus applied to the rollers during the final closing movement of the switch operating mechanism will be transmitted through levers 49 to points on the sleeve 55 42 that are spaced from the plane of the contact blocks 53. The resilient sleeve 42 is spread laterally by the pressure to carry the contact surfaces 54 into engagement with the jaw element. This transmission of pressure through the levers 60 to the tube wall at some distance from the plane of contact engagement has the advantage that the resiliency of the elements in the path of pressure transmission results in good contact pressures in spite of such variations in the dimensions of the parts as may arise during manufacture or through wear.

The several illustrated constructions are indicative of the wide latitude in the design and method of operation of disconnecting switches which embody the invention.

I claim:

1. A disconnecting switch comprising a jaw element, a contact blade, means supporting said blade for movement to carry one end thereof into

the jaw element, said end of the blade being of closed tubular form and provided with opposed contact portions for engagement with the jaw element, and operating means for moving said blade to position the contact portions within the jaw element and thereafter to spread said contact portions into engagement with the jaw element.

2. A disconnecting switch comprising a jaw element, a pivotally mounted blade element having a substantially closed tubular end for entering the jaw element, contact surfaces carried by said tubular end, and operating mechanism for imparting angular movement to said blade, said mechanism including means extending into the tubular end of said blade to force said contact surfaces apart and into engagement with said jaw element.

3. A disconnecting switch as claimed in claim 2, wherein said contact surfaces are rigidly secured to said tubular end of the contact blade, and said means includes members movable to deform the tubular end.

4. A disconnecting switch as claimed in claim 2, wherein said contact surfaces are provided on blocks movably supported within and having contact portions extending through the wall of the tubular end of said contact arm.

5. A disconnecting switch comprising a jaw element, a tubular contact blade, means mounting said blade for pivotal movement to carry the free end thereof into and out of said jaw element, diametrically opposed contact blocks carried by the free end of said contact blade, a shaft substantially coaxial with said tubular element and a crank arm projecting therefrom adjacent said blade mounting means, means operable upon angular motion of said shaft to force said contact blocks apart, and operating means connected to said crank arm to effect pivotal movement of said blade and angular movement of said shaft when the blade is positioned within said jaw element.

6. A disconnecting switch comprising a jaw element, a tubular contact blade, means pivotally supporting one end of said blade, the free end of said blade being substantially complete circumferentially, an end cap closing the free end of said blade, contact blocks carried by the free end of said blade, resilient means tending to draw said contact blocks towards each other to decrease the separation of the contact surface thereof to less than the gap of said jaw element, and operating means including a shaft within said contact blade for forcing said contact blocks apart at the final stage of a closing movement of the disconnecting switch.

7. A disconnecting switch comprising a jaw element, a contact blade and means at one end thereof providing a pivotal support for said blade, contact blocks carried by the free end of said blade, a shaft rotatably mounted within said blade and having a crank arm projecting therefrom adjacent the pivoted end of said blade, means operable by angular movement of said shaft to spread said contact blocks apart, resilient means opposing such spreading movement, and operating mechanism for said blade connected to said crank arm.

8. The invention as claimed in claim 7, wherein

said blade is a substantially closed thin-walled tube of resilient metal, said contact blocks are rigidly secured to said tubular contact blade, and said spreading means includes means for deforming the tubular contact blade.

9. A disconnecting switch comprising a jaw element, a tubular contact blade, means pivotally supporting the blade at one end thereof, contact blocks carried by the other end of said blade, a shaft rotatably mounted within said blade and having a crank arm adjacent the supported end of said blade, operating means connected to said crank arm for imparting pivotal movement to said blade and angular movement to said shaft, and means actuated by angular movement of said shaft to contract said tubular contact blade in a plane normal to the plane of said contact blocks, thereby to spread said blocks apart.

10. The invention as claimed in claim 9, wherein in said blade-contracting means comprises eccentric on said shaft, eccentric rings journalled on said eccentric, headed studs extending through the wall of said blade and secured to said eccentric rings, and pressure-distributing plates between the heads of said studs and the blade.

11. A disconnecting switch comprising a jaw element, a tubular contact blade, means pivotally supporting the blade at one end thereof, contact blocks carried by the other end of said blade, a shaft rotatably mounted within said blade and having a crank arm adjacent the supported end of said blade, operating means connected to said crank arm for imparting pivotal movement to said blade and angular movement to said shaft, and means actuated by angular movement of said shaft to expand said tubular contact blade in the plane of said contact blocks.

12. The invention as claimed in claim 11, wherein said blade-expanding means comprises a plurality of levers within said blade, a wedge member on said shaft for pressing said levers outwardly upon longitudinal movement of the shaft, and cooperating cam members on said blade and shaft for effecting axial movement of said shaft upon angular movement of the same.

13. In a disconnecting switch, a tubular contact blade having means at one end for pivotally supporting the blade, diametrically opposed contact blocks at the free end of said blade, a shaft within and extending longitudinally of said blade, means supporting said shaft for angular motion about its axis, and means operable by angular motion of said shaft to spread said contact blocks apart.

14. The invention as claimed in claim 13, wherein said blade is of resilient metal, and said block-spreading means comprises means for contacting said blade in a plane normal to the plane of said contact blocks.

15. The invention as claimed in claim 13, wherein said contact blocks are separate from and secured to said blade by spring arms tending to move said blocks towards each other, said blocks having contact portions extending through openings in said tubular blade; and said block-spreading means includes a cam on said shaft, and spring means between said cam and said blocks.
